[57] CLAIM

The ornamental design for a contact lens package, as shown and described.

DESCRIPTION

FIG. 1 is a perspective view of a contact lens package showing our new design;

FIG. 2 is a top plan view;

FIG. 3 is a side elevational view, the opposite side being a mirror image thereof;

FIG. 4 is a rear elevational view;

FIG. 5 is a front elevational view;

FIG. 6 is a bottom plan view; and

FIG. 7 is a perspective view thereof in an exploded condition.
